UNITED STATES PATENT OFFICE.

HEINRICH BECKER, OF KIEL-HASSEE, GERMANY, ASSIGNOR TO FRIED. KRUPP GERMANIAWERFT AKTIENGESELLSCHAFT, OF KIEL-GAARDEN, GERMANY.

CYLINDER FOR INTERNAL-COMBUSTION ENGINES.

Application filed May 18, 1926, Serial No. 110,004, and in Germany June 20, 1925.

The invention relates to double-acting two-stroke internal combustion engines having scavenging ports, and has in particular reference to a cylinder arrangement for engines of this type, in which the inlet and outlet passages are for the scavenging air lodged in a supporting piece resting on the frame of the engine and transmitting the forces.

A preferred embodiment of the subject-matter of my invention is illustrated by way of example in the drawing which accompanies and forms part of this specification, the parts in consideration of the engine being shown in vertical section.

15 The working cylinder of the engine is lodged in a supporting piece A which rests upon standards B and has arranged in it, in a manner known per se, the passages a^1 , a^2 which serve to admit and lead off the scavenging air. The cylinder proper is substantially composed of three parts, viz a middle piece C, partly double-walled, two liners D of analogous construction and two cooling jackets E, likewise of analogous construction.

25 The outer wall c^1 of the middle piece C is centered in the supporting piece A and is carried by the latter through the intermediary of a flange c^3 provided on its upper end. The lower end of wall c^1 is able to freely expand in longitudinal direction within the lower end of the supporting piece A. The inner wall c^2 of the middle piece C extends but for a small distance on both sides beyond the inlet and outlet ports c^4 , c^5 provided therein, its extremities have an enlarged inner diameter so as to receive the liners D which are centered on these places relatively to the middle piece C. The portions of the liners D extending beyond the supporting piece A

35 are surrounded by tubular cooling jackets E, the inner ends of which abut against the supporting piece A, said flange c^3 transmitting on the upper side the pressure of this abutment.

45 The whole three-part working cylinder is held together by the pressure of the cover screw bolts F, the inner ends of which are screwed into the supporting piece A. The pressure exerted by the covers G is transmitted on both sides over the flanges d^1 of the liners D and the jackets E onto the support-

ing piece A, this transmission taking place on the upper side by the intermediary of flange c^3 . The inner ends, however, turned to one another, of the liners D are able to 55 freely expand in longitudinal direction with relation to the inner wall c^2 of the middle piece C.

As it will clearly be seen, the described arrangement first results in a very simple and clear structure and an extremely simple shape of the individual elements of the cylinder, this feature being of particular importance with engines of great power in which the described arrangement is destined to be 60 used in the first place. Especially the cooling jackets E and liners D are quite simple tubular bodies, this offering an advantage, in particular with the liners D as these parts are most exposed to wear and are enabled, owing to this simple shape, to be cheaply manufactured of the best adapted material and to be exchanged easily.

65 As, further, the middle piece C is double-walled but for a comparatively small portion of the entire length of the cylinder, its manufacture is considerably simplified.

70 Another important progress is obtained by the described cylinder in so far as the parts C, D, which are most exposed to the noxious 75 action of the hot gases, are able to freely expand, namely the liners D within the middle piece C and this latter within the supporting piece A.

75 Instead of being screwed into the supporting piece A, the bolts F may be united so as to form tie-rods extending from cover to cover.

Claim:

80 In a vertical double-acting two-stroke internal combustion engine: a cylinder, a piece supporting the cylinder, scavenging passages lodged in said supporting piece, said cylinder comprising a double-walled middle piece having ports for scavenging air correspond- 85 ing to said passages of the supporting piece, the outer wall of said middle piece corresponding in length to said supporting piece, a flange connection between the upper ends of said supporting piece and said middle piece, two jackets forming a prolongation 90 of each of the outer wall of said middle piece,

two liners forming prolongations of the inner walls of said middle piece, flange connections between the outer ends of said jackets and said liners, connections between the inner ends of said liners and the inner wall of said middle piece adapted to permit free expansion of said liners with relation to said

middle piece, covers abutting against the outer ends of said liners and screw bolts connecting said covers to said supporting piece. 10

The foregoing specification signed at Hamburg, Germany, this twenty-seventh day of April, 1926.

HEINRICH BECKER.
